UNITED STATES PATENT OFFICE

92,775

DESIGN FOR A DISPLAY BOX

Ioji Sekine, New York, N. Y.

Application November 5, 1932, Serial No. 45,770

Term of patent 7 years

To all whom it may concern:

Be it known that I, IOJI SEKINE, a subject of the Emperor of Japan, residing at New York, in the county of New York and State of New York, have invented a new, original, and ornamental Design for Display Boxes, of which the following is a specification, reference being had to the accompanying drawing, forming part thereof.

Figure 1 is a perspective view of the display box showing my new design with the box wrapped with cellophane or any similar transparent material so that it is dust-proof.

Figure 2 is an end view showing the display box with bevelled exterior sides.

Figure 3 is a plan view of the display box showing my new design.

This invention relates to a new and original design for a box for holding and displaying tooth brushes. It is made of paper or cardboard and is formed with an inner compartment having straight perpendicular walls and a bottom, and an outer casing having sloping sides which are inclined inward or converged toward the upper edge of the box. The box is wrapped with cellophane and the top is open with the exception of the cellophane covering.

Having thus described my invention, I claim—

The ornamental design for a display box as shown and described.

In testimony whereof I affix my signature.

IOJI SEKINE.
